United States Patent Office.

THOMAS J. WELLS, OF ST. ANTHONY, MINNESOTA.

Letters Patent No. 61,493, dated January 22, 1867.

IMPROVED PEAT CAR.

The Schedule referred to in these Letters Patent and making part of the same.

TO ALL WHOM IT MAY CONCERN:

Be it known that I, THOMAS J. WELLS, of St. Anthony, in the county of Hennepin, and State of Minnesota, have invented a new and improved Peat Car; and I do hereby declare that the following is a full, clear, and exact description thereof, which will enable others skilled in the art to make and use the same, reference being had to the accompanying drawings, forming part of this specification, in which—

Figure 1 is a side view of my invention.

Figure 2, an end view of the same, partly in section.

Similar letters of reference indicate like parts.

This invention relates to a new and improved car for transporting and drying peat blocks or bricks from the machine or place where they are prepared to the drying-house, where they remain until they become sufficiently dry for fuel.

The invention consists in a novel construction of the car, as hereinafter fully shown and described, whereby one person is enabled to load and unload the car with the greatest facility.

A represents the bottom or bed of the car, which is mounted on four wheels B. This bottom or bed is a rectangular frame, provided with transverse slats *a*, placed at an equal and suitable distance apart. To one side of this bottom or bed A there are secured two uprights, C C, between which a series of frames, D, is pivoted, as shown at *b*. These frames are constructed precisely similar to the bed or bottom A of the car, with the exception that they are not quite so heavy, the side and end timbers being much lighter. The front parts of these frames have each a pendent screw or rod, *e*, in them, one at each end, to serve as a support for the same, the screws or rods of one frame resting upon the front end of the frame directly underneath it. The uppermost frame D has a leg, E, attached to it at each end and at its outer or front part by pivots *d*, the lower ends of said legs fitting in staples *e* at the front and rear ends of the bed or bottom A of the car. The uprights C C are each formed with a shoulder, *f*, to serve as bearings for the legs E when the uppermost frame D is raised, as shown in red in fig. 2. The lower frames are retained in an elevated state by hooks *g*, the hook of one frame being fitted in a staple in the frame immediately below it. In loading the car all the frames D are elevated, and the bed or bottom A is first loaded with the peat blocks or bricks; the lowermost frame D is then lowered and filled and the other frames lowered and loaded consecutively. In unloading the car the blocks or bricks are taken from the uppermost frame D, which, when empty, is raised and supported by the legs E resting on the shoulders *F* of the uprights C C, and the other frames are consecutively unloaded and hooked to the frame immediately above it.

By this simple arrangement one person may load and unload the car with the greatest facility.

Having thus described my invention, I claim as new, and desire to secure by Letters Patent—

A car for transporting and drying peat, constructed with a series of frames, arranged substantially in the manner as herein shown and described.

THO. J. WELLS.
